(57) **CLAIM**

The ornamental design for an ankle slipper as shown and described.

DESCRIPTION

FIG. 1 is a perspective view of an ankle slipper according to an embodiment of my new design;

FIG. 2 is a left side elevation view of the ankle slipper shown in FIG. 1;

FIG. 3 is a front elevation view of the ankle slipper shown in FIG. 1;

FIG. 4 is a rear elevation view of the ankle slipper shown in FIG. 1;

FIG. 5 is a top plan view of the ankle slipper shown in FIG. 1; and,

FIG. 6 is a bottom plan view of the ankle slipper shown in FIG. 1.

All portions of the drawings shown in dashed lines are for illustrative purposes only and form no part of the claimed design.

1 Claim, 5 Drawing Sheets
